UNITED STATES PATENT OFFICE.

HOWARD T. HALLOWELL, OF PHILADELPHIA, PENNSYLVANIA.

PULLEY.

SPECIFICATION forming part of Letters Patent No. 732,549, dated June 30, 1903.

Application filed December 21, 1901. Serial No. 86,856. (No model.)

To all whom it may concern:

Be it known that I, HOWARD T. HALLOWELL, a citizen of the United States, residing in the city and county of Philadelphia, State 5 of Pennsylvania, have invented a new and useful Improvement in Pulleys, of which the following is a specification.

My invention consists of an improved construction of pulley, which has been designed 10 to overcome the defects common in pulleys now in use, since the wooden hubs which are usually used in wooden pulleys are always changing with the conditions of the atmosphere, thereby making them clamp the shaft 15 very uncertainly, excepting under exceptionally favorable conditions. In wooden-hub pulleys heretofore manufactured it has been necessary for strength to make the hub of abnormal size, which has caused the same to 20 act as a fan having huge and unsightly revolving paddles.

By my construction I employ a metallic hub-shell and metallic angular arms extending therefrom to the rim of the pulley, where- 25 by any size diameter of pulley can be made by using the proper angles and any width of face can also be made with equal ease and with increased strength by simply separating the angles on the hub-shell to correspond with 30 the face of the pulley, or in certain cases other angles, T's, or the like may be inserted within the outer angles to give the requisite increased strength. By the use of my novel construction of hub-shell and its adjuncts I 35 can make a hub projecting from the arms of the pulley.

Figure 1 represents a side elevation of a pulley embodying my invention, wherein I have shown the same as a pulley having a 40 steel hub and a wooden rim. Fig. 2 represents a section of the hub on line $x x$, Fig. 1, omitting the bushing-sections 8. Figs. 3, 4, and 5 represent detail views showing different devices which may be employed for se- 45 curing the spokes of the pulley to the rim thereof. Fig. 6 represents a side elevation of a portion of the hub-shell and clamp em- ployed, showing lips acting as a key. Fig. 7 represents a side elevation of a portion of the 50 hub-shell and its adjuncts, showing also a plate connecting and stiffening the flanges of the angles therein. Fig. 8 represents a longi-

tudinal sectional view showing one form of construction for securing the angle-iron spokes to the hub-shell. Fig. 9 represents 55 a modified construction, partly in section, wherein I have dispensed with the hub-shell preferably employed. Fig. 10 represents another modification, wherein I locate the hub-shell on the outer side of the angle-flanges 60 employed. Fig. 11 represents a side eleva- 65 tion of a pulley, but showing the arms deflected at their edges for the purposes of strength and to enable them to cut the air more readily. Fig. 12 represents a side eleva- 70 tion of the bushing which may be employed in conjunction with my improved pulley. Fig. 13 represents a section on line $z z$, Fig. 12. Figs. 14 and 15 represent transverse 75 sectional views on line $z z$, Fig. 12, show- 80 ing a modification which may be employed. Fig. 16 represents a side elevation showing the hub of the pulley provided with angle-iron spokes having deflected flanges and tapering portions. Fig. 17 represents a side 85 elevation similar to Fig. 16, but showing a modified construction of spokes. Fig. 18 rep- 90 presents a front elevation, partly in section, showing one form of spokes or arms which may be employed. Fig. 19 represents an ele- 95 vation of another form of pulley. Fig. 20 represents a sectional view showing a portion of the rim of another embodiment of my in- vention. Figs. 21 and 22 represent side eleva- 100 tions of modifications. Fig. 23 represents a side elevation of a modification.

Similar numerals of reference indicate cor- responding parts in the figures.

Referring to the drawings, referring first to Fig. 1, I have shown as one embodiment of 90 my invention a pulley 1, provided with a wooden rim 2, to which are secured the angular arms 3, forming the main portion of the pulley and consisting of the flanges 4 and 5, whose extremities may be secured to the con- 95 tiguous portions of the wooden rim by means of the lips 6, which project from the angular arms 3 and are adapted to fit in contiguous saw-kerfs in the wooden rim 2. The arms 3 are preferably swelled out or provided with re- cesses at about their central portion, at which point is located the hub-shell 7, the latter be- 100 ing made in sections, as will be understood from Fig. 1, and containing the bushing-sec-

tions 8, between which is located the shaft 9. It will be seen that the flanges 4 and 5 project endwise outwardly to the rim from the curved depression, forming lateral and diametric 5 strengthening means. The arms 3 are held in their proper position by means of the fastening devices 10 and 11, and at the extremities of said arms are employed the additional fastening devices, which are of the form seen in 10 Fig. 1 at 12, or, if desired, the construction seen in Figs. 3, 4, and 5 at 12^a, 12^b, and 12^c, respectively, may be employed, the fastening devices seen in Fig. 4 being constructed, preferably, as shown, while in Fig. 5 I have shown 15 a plate or brace as being employed. The dotted portion of the device 12^a shown in the rim is made with a flange-lip. This lip (shown dotted) enters a sawed groove in the rim. Under this lip I have shown another 20 piece, (also dotted,) which is intended to assist in distributing the load over the entire face of the pulley, especially when the rim is composed of the familiar small wooden segments, a construction old to the art. I wish 25 also to use this footing-piece under lip of the device 12^a, so that after the pulley is assembled this footing-piece may be driven firmly into place, thus securely tying the arms to the rim and enabling the arms to be fastened 30 to the rim at a suitable distance from where the rim is parted for a split pulley, thus greatly strengthening the junction. It will be noticed that these arms 3 are continuous from one side of the pulley to the other and 35 each hub-shell is secured to a contiguous arm and the said arms form the main portion of the pulley.

In the construction of large pulleys I further brace and reinforce the same by the employment of the supporting-spokes 13, which are preferably assembled and secured in position as shown in Fig. 1.

In Fig. 6 I have shown the hub-shell 7 as secured to the contiguous arm 3, which latter 45 also serves as a support for the clamp or strengthening device 14, the hub-shells in this case having lips which act as keys, so that when bushings are employed the rivets securing the hub-shells to the arms or angles 3 will 50 not be easily sheared by the torsional strain when the pulley is clamped to the shaft. The projecting end portions 15 of the hub-clamps are to receive the clamp-bolts, thereby reinforcing the hub portion of the angle-iron 55 arms, so that the metal of the arms will not spring when the bolts or clamping devices are tightened. These reinforcing devices may be made in various ways without departing from this invention.

60 In Fig. 7 I have shown the arm or angle 3, to which the hub-shell 7 is secured, strengthened and reinforced by a plate 15^a, which connects and acts as a bridge to stiffen the flanges of the angles, and I have in this instance 65 shown said flanges as sheared at the point 16, and said bridge may be used in connection

with the construction shown in Fig. 11, if desired.

In Fig. 8 I have shown a sectional view of another manner of securing the hub-shell 7 70 in position, wherein 17 designates angle-iron spoke-flanges secured to said hub-shell, which latter is provided with a recess or hole 18, in which is seated a trunnion 19 of the bushing 20 when the latter is employed. 75

In Fig. 9 I have shown a slightly-modified construction, wherein the hub-shell is dispensed with, the shaft 9 being held in position in substantially the manner described and the flanges 4^a connected by the bolts 4^b. 80

It is desired for small-diameter pulleys to dispense with hub-shells, as the angle-iron spokes are sufficiently rigid laterally; but I prefer to use the hub-shells in most cases.

In Fig. 10 I have shown the hub-shell 7 as 85 placed on the outer portion of the angle flanges or arms 3.

In Fig. 11 I have shown a pulley 21 with a metal rim 22 and arms 23, which are provided with the hub-shell sections 7, already described, said arms, however, having the deflected flanges 24, whereby great strength and rigidity are attained and the air is enabled to be readily cut as the pulley revolves. If desired, I may construct the rim 22 as shown 95 at the joint 25, where the abutting terminals thereof are turned inwardly, or, if desired, I may construct the rim having its abutting portions located end to end, as indicated at 26, it being apparent that either or both of 100 the fastening means 27 or 28 may be employed to secure the parts in assembled position.

The angle-iron spokes 23 (seen in Fig. 11) may have the flanges on their outer ends turned up, forming feet to which the rim may 105 be secured.

It will be apparent that the angles may not extend straight from the center or hub to the rim, as now shown, but they may come nearer together at the rim-joint than they are at the 110 hub, thereby dispensing with the washers 30, if desired.

When the construction seen in Fig. 11 is employed, I consider it essential to use the spokes 29 in order to support and strengthen 115 the rim 22; but it will be apparent that the spokes may be made differently from the form shown and they need not necessarily have feet thereon, as shown in the present instance.

For large-diameter pulleys I prefer to use 120 semicircular strengthening-rings, which are adapted to be attached to the spokes 29 and the angle-irons 23, it being understood that the semicircular rings may be made of such diameter so that the spokes 29 and 23 may be 125 rigidly connected at a suitable distance between the hub and rim portions of the pulleys. A small-size ring showing the principle is better shown in Fig. 23, which may be equally applied to Fig. 1. 130

It will be apparent that, if desired, I may employ two fastening means (shown in Fig.

11) in the same pulley, although it will be understood that in practice I may, if desired, employ one or the other fastening devices, according to requirements.

5 The bushing 20, (seen in Fig. 12,) as already explained, is provided with trunnions 19, which are adapted to coact with the recess 18, (seen in Fig. 8,) said trunnions 19 being supported by a connecting-bridge 34, seen in section 10 in Fig. 13, where is cut away a great excess of metal, it being apparent that, if desired, I may cast the bushing solid, as shown in Fig. 13, and by means of a drift split the same after it has been machined, or, if desired, 15 the bushing may be separated by an ordinary cutting tool, a special feature, to which I desire to call attention, being that I do not finish the bore of the bushing, excepting at the ends, thereby saving considerable time and 20 expense. The bushing may be cast without being split, it being, however, apparent that the bridge shown in section, connecting the two finished ends 35 and 36, is the same as the bridge and its adjuncts seen in Fig. 13.

25 In Fig. 15 I have shown a construction of bushing wherein I carry the bridge or connecting-rib farther around circumferentially; but this rib is not finished, although where the bushing is very thin I may find it necessary to finish the connecting-rib, which lies next to the inner bore thereof.

It will be understood that I need not necessarily split my bushing, but that the same can be made without necessitating the finishing of that portion under the trunnion, no matter whether the trunnion be located on a rib that is the width circumferentially as seen in Fig. 15 or not.

35 In Fig. 16 I have shown the spokes 41 as constructed of angle-irons having deflected flanges, said spokes being also shown as tapering, it being understood that the hole 42 is for the insertion of the trunnion 19 of the bushing employed, which may be any of the 40 forms seen in Figs. 14 and 15.

45 In the construction seen in Fig. 17 I have shown the angles or spokes 43 as provided with deflected flanges, or, if desired, said spokes may be of any shape, as indicated at 50 44, it being of course understood that I can either deflect the flanges from end to end, as seen in Fig. 16, or partially, as seen in the upper portion of Fig. 17, or not at all, as indicated in the lower portion of said latter figure.

55 It will be apparent that, if desired, I may employ the construction of spokes seen in Fig. 17 in the same pulley, or, if deemed expedient, I may employ either form, according to 60 requirements.

It will of course be apparent that, if desired, the spokes may be either secured directly to the rim 46 or secured to either angle or T irons, which may be either partially or 65 wholly within the semicircumference of the pulley.

In Fig. 18 I have shown the spokes 52 as made of slightly-different contour, the construction seen therein being applicable for pulleys having a narrow face of small diameter, it being, however, preferable in practice to make the spokes of angle-iron, since no new dies will be necessary.

70 In Fig. 19 I have shown a slightly-modified construction of a hub-shell and spokes of a pulley.

75 In Fig. 20 I have shown another embodiment of my invention wherein I employ a channeled segment, as 53, which may be secured within the pulley-rim 54.

80 It will thus be seen from the foregoing that while I have shown various embodiments of the principle of my invention I have followed in each case the same general construction for the hub, wherein I have employed a plurality 85 of angle-irons, to which a separable hub-shell is attached for each half of the pulley.

85 Other modifications may be resorted to without departing from the principle of the invention, and in Figs. 21, 22, and 23 I have 90 shown some of those that occur to me at this time.

It will be apparent that the broad feature of my invention is applicable to rims made either from paper, steel, wood, or other material and that various modifications involving slight changes in the ends of the angles and the manner of securing the angles to the rim may be made by those skilled in the art which will fall within the scope of my invention. The angles, arranged in substantially diametrical relation to the rim in conjunction with the hub-shell, are an important feature of my invention; but it will be apparent that the hub-shell may be omitted, said shell 105 acting in reality as a hub and also as a means for tying the angles in their respective positions. I also attach importance to the use of the deflected flanges on the spoke-arms, as seen in Figs. 16, 17, 18, whereby great rigidity is attained and the flanges are enabled to 110 cut the air as the pulley revolves.

105 In many size pulleys where strength is not desired I prefer to shear the flanges of the spoke-arms instead of deflecting them.

115 Having thus described my invention, what I claim as new, and desire to secure by Letters Patent, is—

1. A diametrically-parted pulley, each part of which is provided with two separate angle-iron spoke-bars approximately equal in length to the diameter of the pulley, each separate spoke-bar being provided with a curved depression at substantially the central portion thereof, a rim, each of said angle-iron spoke-bars having both its flanges which comprise the same projecting endwise outwardly toward the rim from said depressions, means securing the ends of the spoke-bars to the rim adjacent its meeting edges, shaft-fitting hub-shells secured in said depressions against rotary movement and clamping-bolts passing 120 125 130

through and engaging the flanges of said angle-iron spoke-bars and securing them together with a space laterally therebetween.

2. A parted pulley comprising a rim portion, four separate angle-iron spoke-bars, said spoke-bars approximately equal in length to the diameter of the pulley and formed with curved depressions at substantially the central portion thereof, both flanges forming said angle-bars projecting endwise outwardly from the said depressions toward the rim, fastening devices securing the outer ends of the spoke-bars to the rim and clamping devices passed through and engaging the flanges of said angle-iron spoke-bars and securing them with spaces laterally and diametrically between them.

3. A parted pulley comprising a rim portion, four separate angle-iron spoke-bars, said spoke-bars approximately equal in length to the diameter of the pulley and formed with curved depressions at substantially the central portion thereof, both flanges forming said angle-iron bars projecting endwise outwardly from the said depressions toward the rim, fastening devices securing the outer ends of the spoke-bars to the rim, and clamping devices passed through and engaging the flanges of said angle-iron spoke-bars and securing them with spaces laterally and diametrically between them, combined with circular shaft-fitting hub-shells located in said depressions.

4. A parted pulley comprising a rim portion, four separate angle-iron spoke-bars approximately equal in length to the diameter of the pulley and formed with curved depressions at substantially the central portion thereof, said angle-iron spoke-bars having their lateral and diametric flanges projecting endwise outward toward the rim from said depressions, means securing said spoke-bars to the rim portion, circular shaft-fitting hub-shells located in said depressions, means securing said spoke-bars together with spaces therebetween, reinforcing bolt-blocks mounted on the flanges of said spoke-bars adjacent said depressions, and clamping-bolts for securing said bolt-blocks in place.

5. A separable pulley embodying a plurality of angle-iron spoke-arms, a sectional rim to each section of which the ends of one of said arms are secured, said arms having curved portions intermediate their ends, hub-shells conforming to and secured within said curved portions, the spokes radiating from said arms and secured to the rim, means connecting said arms near the rim and means connecting said arms upon opposite sides of their curved portions, and sectional metallic bushings interposed between said shells and the shaft of the pulley, the bushing-sections having trunnions mounted in said shells.

6. A pulley embodying a plurality of angle-iron spoke-arms, circular shells, said arms conforming to the contour of said circular shells upon which the said angle-irons are attached and to which they are secured at the

hub portion of the pulley, a bushing received in said shells and interposed between said shaft and pulley-hub, said bushing having two distinct end portions which are adapted to be finished to fit the shaft and pulley-hub, said distinct end portions of bushing being secured together by means of a connecting-rib acting as a bridge over a shaft, a portion of said bridge being adapted to form a trunnion which enters the hub of the pulley, said bushing being finished only on the ends, the intermediate portions being cut away.

7. A pulley, in combination with a metal bushing interposed between the hub portion of the pulley and shaft, said bushing in halves, each half of which enters the corresponding half of the pulley, said bushing consisting of two end portions finished to fit the shaft and pulley-hub, and ribs on the end portions of the bushing, in combination with a longitudinal connecting-bridge over said shaft and upon which bridge a trunnion is mounted for the purpose of entering a suitable recess in said pulley-hub.

8. A pulley, in combination with metal bushings interposed between the hub portion of the pulley and shaft, said bushings being in halves and consisting of two distinct end portions, said portions united by a longitudinal connecting-rib carrying a trunnion adapted to enter suitable recesses in said pulley-hub, said bushings being separated with end portions finished.

9. A pulley embodying a hub portion, and separable metal bushing comprising end portions, a connecting-rib, and trunnions carried thereby to engage in recesses in the pulley-hub, the said portions having end portions finished.

10. In a separable pulley, semicircular shells, rim portions, angle-iron spoke-arms conforming to said semicircular shells at the hub portion of said angle-irons, to which shells the angle-irons are secured, said semicircular shells receiving the shaft of the pulley combined with semicircular bushings interposed between the rim portions of said shells and shaft, said bushings having trunnions adapted to enter recesses in said shells attached to angle-iron spoke-arms.

11. In a pulley, angle-iron spoke-arms, a sectional rim to which the ends of one of said arms are secured, said arms having curved portions intermediate their ends, hub-shells conforming to and secured in said curved portions, sectional trunnioned bushing and strengthening members conforming to the shape of the arms at the hub portion.

12. In a pulley, angle-iron spoke-arms, a sectional rim to which the ends of said arms are secured, said arms having curved portions intermediate their ends, hub-shells conforming to and secured in said curved portions, sectional trunnioned bushing and strengthening members having lips acting as keys and conforming to the shape of the arms at the hub portion.

13. A parted pulley comprising a separate rim portion, four separate angle-iron spoke-bars, said bars in length being approximately equal to the diameter of the pulley and formed with curved depressions at substantially the central portion thereof and with lateral and diametric flanges projecting endwise outwardly toward said rim from said curved depressions, means securing said spoke-bars together with a space intervening, means attaching the ends of the spoke-bars to the rim portion adjacent the meeting edges thereof, separate auxiliary spoke-arms, means attaching the same to said rim and to the flanges of said angle-iron spoke-bars adjacent their curved depressions and fastening devices passing through and engaging the flanges of said angle-iron spoke-bars adjacent the curved depressions, and curved portions secured within said curved depressions. 30
- 15 14. A parted pulley comprising a separate rim portion, four separate angle-iron spoke-bars, said bars in length being approximately equal to the diameter of the pulley and formed with curved depressions substantially at the center and with lateral and diametric flanges 35
